Specification for Design.

Patented Mar. 15, 1921.

Application filed June 6, 1919. Serial No. 302,339. Term of patent 8½ years.

To all whom it may concern:

Be it known that I, ADA W. ELLSWORTH, a citizen of the United States, residing at Chicago, in the county of Cook and State of Illinois, have invented a new, original, and ornamental Design for a Child's Coat, as shown in the accompanying drawings.

In the drawings:

Fig. 2 is a rear view thereof.

What I claim is:—

The ornamental design for a child's coat, as shown.

In testimony whereof I have hereunto set my hand and seal at Chicago, Illinois, this 29th day of May, 1919.

ADA W. ELLSWORTH.
